UNITED STATES PATENT OFFICE.

GEORGE BRINKER BARRON, OF EASTON, PENNSYLVANIA.

SWITCH-OPERATING DEVICE.

SPECIFICATION forming part of Letters Patent No. 606,499, dated June 28, 1898.

Application filed December 14, 1897. Serial No. 661,834. (No model.)

To all whom it may concern:

Be it known that I, GEORGE BRINKER BARRON, a citizen of the United States, residing at Easton, Pennsylvania, have invented certain 5 new and useful Improvements in Switch-Operating Devices, of which the following is a specification.

My invention is an improvement over the devices made the subject of Letters Patent 10 granted me on the 2d of February, 1897, No. 576,424; and it is the object of the invention to simplify the construction and make it more effective.

In the accompanying drawings, Figure 1 15 shows a plan view of the switch-tongue and its operating mechanism, while Fig. 2 is a side elevation of the same. Fig. 3 shows the means carried by the car for actuating the devices controlling the switch-tongue; and Figs. 4, 5, 20 6, 7, and 8 are details of this construction.

Referring to Figs. 1 and 2, the switch-tongue is shown at *a* and is shifted by the positively-actuated pusher *b*. The inner end of the pusher *b*, which is horizontal, is connected to the forked end of a horizontal pivoted bell-crank *c*, and the end of the bell-crank is connected to a link *d*, which in turn, at its opposite end, is connected to an upright *e*, forming a part of a sleeve *f*. The sleeve *f* 30 has a projection *g*, which, with the upright *e*, practically forms a bell-crank, and this projection is connected by link *h* with a weighted lever *i*, pivoted at *k* and having its opposite end extending upwardly in contact with the bottom of a pivoted lever or cover plate 1, 35 having a raised surface *m*, with its ends inclined to the surface of the boxing inclosing the parts. It will be seen that on the depression of the pivoted cover 1 the upper end of the lever *i* will be depressed, the lower end raised, the sleeve *f* rocked, and through the connections described the pusher *b* will be moved laterally to shift the tongue. As soon as the pressure upon the pivoted cover 1 has 40 been removed the weight of the lever *i* will return the parts to their normal position. In order to depress the lever or cover 1, I provide means carried by the car and under the control of the driver or motorman. As shown 45 in Fig. 4 and the following, the pilot-board *A* has secured to it a flanged plate *a'*, and fitting the flanges of this plate, so as to be

guided thereby, is a movable frame *B*. This plate has brackets 2 projecting from its lower end at each side, and these brackets carry the 55 roller *C*, and this roller is adapted to be raised or lowered and when lowered is used to depress the lever or cover 1, and thus operate the switch-tongue. It will be observed that when this roller is lowered it is necessary to 60 lock it in place, or else the rigidity of the devices used to throw the switch-tongue may be sufficient to overcome the weight of the roller, and thus raise the roller instead of having the roller operate the pivoted cover 1 to depress the same. To this end I use a lever *e'* of bell-crank shape and pivoted to the frame *B* at 3. One end of this lever is upright and the other is horizontal. When the frame *B* with its roller is in the lowest position, the upright 70 end of the lever *e'* slips under a projection 4, carried in the center of the plate *a'*, as shown in Fig. 3, and this holds the roller down to its work. The roller is lifted by means herein-after described; but the first action must release the end of the lever *e'* from the projection or stop 4. This is accomplished by forming a 75 ring or eye 5 on the horizontal end of the lever *e'*, and a rod 6 extends from this eye to operating means, so that the first action in the lifting of the rod 6 is to swing the vertical end of the lever *e'* out from under the stop, and then the roller is free to be raised. The horizontal end of the bell-crank has a projection 80 7, which works in a slot 8 in the movable frame *B*, and this allows sufficient movement to free the lever *e'* from the stop 4, after which in the continued upward movement of the rod 6 the frame *B* is also lifted with its roller. The frame *B* is provided with a cut-out portion 9, so as to prevent engagement between the frame *B* and the stop 4. 85 90

The rod 6 is connected at one end of the bell-crank 10, pivoted under the car, and from the opposite end of the bell-crank extends a rod 95 11, connecting with the end of a lever 12, pivoted at 13 and having a projection 14 extending into the groove of a snail-cam 15, the cam being operated by an ordinary hand-lever fitting its squared socket 16. 100

What I claim is—

1. The combination with a switch-tongue, a pusher therefor disconnected from the same, a pivoted lever projecting above the surface

and operating connections between the pivoted lever and the pusher including a weighted lever for transmitting the depression of the projecting lever to the switch-tongue, the 5 weighted lever returning both the pusher and the projecting lever to normal position, substantially as described.

2. In combination, a switch-tongue, a horizontal pusher disconnected from the same, a 10 weighted lever, a cover projecting above the surface pivoted independently of said lever and supported by the same and operating connections between the weighted lever and the pusher, substantially as described.

15 3. In combination with a switch-tongue, and operating means therefor, a car and means carried by the car for actuating the switch-tongue-controlling device, consisting of a roller, a vertically-movable depressor and 20 locking means for said depressor, with means positively operated for both operating the locking means and lifting the depressor, substantially as described.

4. In combination with a switch-tongue and means for operating it, a roller carried by the 25 car vertically movable thereof, a stop and a lever movable with the roller and independently of the same adapted to engage said stop and means for releasing the lever and lifting the roller, substantially as described. 30

5. In combination with the pilot-board of a car, a movable frame B, a roller carried thereby, a bell-crank lever also carried by the frame, a stop engaging one end of the lever, a rod 6 engaging the other end, said lever having limited movement and operating connections to the position of the driver or motorman, substantially as described.

In testimony whereof I affix my signature in presence of witnesses.

GEORGE BRINKER BARRON.
